Primary Examiner—Carmen H. Vales-LadoAssistant Examiner—Jeffrey Asch*[57]*CLAIM

The ornamental design for an infant holder for changing diapers, as shown and described.

DESCRIPTION

FIG. 1 is a perspective view of an infant holder for changing diapers showing my new design;

FIG. 2 is a top plan view thereof;

FIG. 3 is a bottom plan view thereof;

FIG. 4 is a side elevational view, the opposite side being a mirror image thereof except without the securing tab members; and,

FIG. 5 is an end elevational view, the opposite end being a mirror image thereof.
